DESIGN FOR A HANDBAG OR SIMILAR ARTICLE

Saul Gordon, New York, N. Y.

Application July 1, 1944, Serial No. 114,282

Term of patent 3½ years

(Cl. D87—3)

To all whom it may concern:

Be it known that I, Saul Gordon, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein,

The rear of the handbag is substantially the same in appearance as the front shown.

The characteristic feature of my design resides in the combination on the handbag disclosed, of the tinsel and corde elements, arranged as shown.

I claim:

The ornamental design for a handbag or similar article, substantially as shown and described.

SAUL GORDON.
